MOUNT FOR ELECTRON DISCHARGE
DEVICES

Julius Hirshmann, Hillside, N. J., assignor, by
mesne assignments, to Radio Corporation of
America, New York, N. Y., a corporation of
Delaware

Application June 27, 1936, Serial No. 87,611

5 Claims. (Cl. 250—27.5)

My invention relates to improvements in electron discharge devices and more particularly to improved means for firmly and accurately positioning the electrode mount within the envelope 5 of a tube.

In modern tubes, such as tubes having dome type bulbs or envelopes, it is found desirable to hold the electrode assembly firmly in place in the envelope to prevent transverse movement of the 10 mount. To this end the dome or other constricted portion of the tube is utilized to steady the electrode assembly against transverse movement and to keep the assembly more firmly established in position than when the assembly is supported and steadied only from the stem press. The 15 mount should be steadied sufficiently to avoid noises, such as clicking, due to contact between the electrode assembly and the envelope when the tube is jarred or vigorously vibrated. The steady- 20 ing means or mount spacer should be sufficiently resilient to avoid the stresses and distortion of the mount assembly produced when a mount with a rigid steady means is forced into a bulb dome smaller than usual. Metallic spring spacers are 25 resilient and easily made and attached to the mount, but the use of such metallic springs to steady the mount has not heretofore been favored because strain checks and cracks were often produced in the glass bulb during exhaust at the 30 points where the metal touched the glass. It is the usual practice to attach to the mount, the mica mount spacers either in the form of a plate or disc extending transversely of the dome portion of the envelope or in the form of vertical 35 oblong shaped micas attached to the mount intermediate their ends and with their ends in contact with the walls of the bulb. Mica mount spacers also have some disadvantages, as commercial mica varies from .008" to .020" in thickness and 40 the resiliency of the mica mount spacers varies considerably within the result that the mounts are not always positioned centrally of the bulb. Attaching the vertical micas to the mount is 45 sometimes difficult and various ways of attaching the mica have been devised. Furthermore, mica may split under stress and sometimes blisters during the high frequency heat treatment. A 50 metallic spring mount spacer or support would in many cases be preferable to a mica spacer if it could be used without harm to the bulb or to the tube.

The principal object of my invention is to hold firmly and accurately the free end of an electrode mount within the bulb of an electron discharge device by metallic springs secured to the mount

and engaging the interior walls of the bulb without injury to the mount during assembly or to the bulb during exhaust. Another object of my invention is to provide such metallic spring spacers which are simple to manufacture and are easily 5 attached to the mount.

The novel features which I believe to be characteristic of my invention are set forth with particularity in the appended claims, but the invention itself will best be understood by reference to the following description taken in connection with the accompanying drawing in which Figure 1 is a partial view in perspective of one form of an electron discharge device embodying my invention; Figure 2 is a horizontal cross section taken along line 2—2 of Figure 1; Figure 3 is a side view of Figure 2; Figure 4 is a view in perspective of one of the spring spacers made according to my invention before being applied to a mica spacer; Figure 5 is a partial view in perspective of a modification of an electron discharge device embodying my invention; Figure 6 is a horizontal cross section taken along the line 6—6 of Figure 5; Figure 7 is a side view of Figure 6; Figure 8 is a partial perspective view of another modification 25 of an electron discharge device embodying my invention; and Figure 9 is a partial perspective view of a still further modification of an electron discharge device embodying my invention.

The electron discharge device shown in Figure 30 1 has a dome type of bulb 10, which is provided with the usual stem press and base not shown. The mount 11 comprises the usual electrode assembly and extends into the tubular portion or dome of the bulb 10. The mount has secured to 35 its upper end by straps 12, welded to the mount, a sheet insulator or electrode spacer 13, preferably of mica, which may be of any shape, but is shown as a disc-shaped plate in Figures 1, 2, and 3 and which extends transversely of the mount and of the tubular portion or dome of the envelope 10.

In view of the fact that the envelopes are not all of exactly the same diameter, rigid mount spacers on the upper end of the mount to fit 45 snugly in the dome are not feasible. If the mount spacers are rigid and fit the largest envelope the mount will be stressed and distorted when a smaller envelope is placed over the mount assembly, while if the spacer fits the smaller envelope, it will be loose in the large envelope and clicking will result.

In accordance with my invention I provide the mica plate 13 with resilient metallic spring spacers 14 in the form of bowed clips which are 55

clipped to and have their ends extending from the edge of the plate 13 into contact with the inner dome of the envelope 10 to resiliently support and steady the mount and center it in the envelope.

One form of spring spacer made according to my invention is best shown in Figure 4. The spacer 14 is provided at each end with a double loop or closely wound coil 15 providing a pair of 10 spring clips between which the mica spacer can be separably engaged. The free ends may be, but need not be bent, as shown at 16. When attached to a mica spacer and inserted in an envelope the fingers of the spring spacer take the 15 position shown in the dotted lines. This arrangement provides a support having the resiliency of a coiled spring.

These metallic spring spacers, which may be made for example of tungsten, molybdenum or 20 nichrome wire may be removably attached as best shown in Figures 2 and 3. These spring spacers are slipped over the edge of the mica plate 13, the plate being engaged between the turns of the coils 15, and the bowed outer ends engage the 25 interior wall of the tubular portion of the envelope. When the bulb is placed over the mount the spring fingers or ends 16 are flexed inwardly toward the axis of the tube to an extent dependent on the inner diameter of the dome of the bulb. 30 These spring spacers resiliently center the mount from the walls within the envelope and prevent clicking of the tube.

I have obtained very good results with nichrome wire of a diameter of .016" (#26 B and S gauge) 35 measuring about $\frac{1}{2}$ " between the centers of the coils 15, the diameter of the coils being between .140" and .156". The distance from the center of the coil to the vertical portions at the end of the spring fingers measured .218". The length 40 of the vertical portions of the fingers was .093". The mica was formed to provide a clearance of about .040" between the edge of the mica and the wall of the envelope, although this dimension is not critical since the metallic spring spacer 45 can be formed to take care of wide variations.

While I do not wish to be restricted to any particular theory, I believe that the success of the metal spring fingers made in accordance with my invention is due to the fact that they are of very 50 small mass and do not absorb very much heat and are heat insulated by means of the mica plate to prevent conduction of heat to and from the mount. As the result the temperature of the spring fingers is always so nearly the same as the 55 temperature of the envelope that the temperature differential between the two is practically negligible, thus preventing the checks and cracks in the glass envelope which are apt to occur when metallic spring spacers are used. A large temperature differential is likely to occur when heat 60 is rapidly conducted from the metallic spring mount spacers to the mount when heating the envelope, or by conducting heat to the spring spacers from the mount during the high frequency heat treatment of the mount.

Because the spring spacer is easily made and 70 easily applied, manufacturing is simplified, there being no need to thread the wire spacer through apertures in the mica or to provide extra means for fastening the metal spring spacers to the mica spacer. This reduces the time required for assembly of the mount. A metal spring spacer made according to my invention has more 75 resiliency than other types of spacers, metal or

otherwise, and hence is capable of taking care of wider variations of bulb diameter.

In a modification shown in Figures 5, 6, and 7 the mica plate 26 has spaced around it, near its edge, slots 21 through which the metallic spring 5 spacers extend, the mount spacers being formed as best shown in Figure 6 to provide a central portion 23 engaging the underside of mica spacer 26 and folded reverse portions 24 engaging the upper surface of the mica spacer 26 to form clips 10 to attach the spring spacers to the mica. Free ended bowed portions or fingers 25 resiliently engage the inner wall of the dome portion of the envelope of the tube.

In the modification shown in Figure 8 the mica 15 plate 26 is provided with slots 27 into which the metallic spring element 28 having spring clips 29 is inserted to position the spring. The spring is clipped to the mica to secure it to the mica 26 by clips 29 so that its ends 30 extend beyond the 20 edges of the mica and contact the interior walls of the tubular portion of the envelope to space the mount within this portion of the envelope.

As shown in the modification in Figure 9 the mica plate 31 may be provided with slots 32 into 25 which portions of the metallic spring elements extend. The spring spacer is provided with a central portion 33 having bent portions 34 engaging the lower surface of the mica plate 31 and reversely bent portions 35 engaging the upper surface 30 of the mica plate 31, these reversely bent portions forming a pair of clips so that the mica plate is clipped between the reversely bent portions 34 and 35. The free ends 36 of the springs 35 extend over the edges of the mica and into contact with the wall of the bulb.

These metallic spring spacers are capable of providing for wider variations of bulb diameters than the usual type of mica spacer and are usually more easily made and attached to the mount 40 and retain their resiliency during the sealing and high frequency treatment of the mount during the exhaust operation.

While I have indicated the preferred embodiments of my invention of which I am now aware 45 and have also indicated only one specific application for which my invention may be employed, it will be apparent that my invention is by no means limited to the exact forms illustrated or the use indicated, but that many variations may 50 be made in the particular structure used and the purpose for which it is employed without departing from the scope of my invention as set forth in the appended claims.

What I claim as new is,—

1. An electron discharge device comprising an envelope having a tubular portion, a mount enclosed by said envelope and comprising an electrode assembly positioned to extend into the tubular portion of the envelope and having a plate of 60 insulating material secured to the end of the mount to extend transversely of the tubular portion of the bulb, and metallic spring spacers provided intermediate their ends with a spring clip for separably engaging the edge of said plate 65 with their ends extending beyond the edges of said plate and engaging the walls of the tubular portion of the envelope to resiliently support the mount within the tubular portion of the envelope.

2. An electron discharge device comprising an envelope having a tubular portion, a mount enclosed by said envelope and comprising an electrode assembly positioned to be at least partially 70 within said tubular portion, a sheet insulator se- 75

cured to said mount to extend transversely of the tubular portion of said envelope, and metallic spring spacers provided intermediate their ends with a pair of spring clips for engaging the edge of the sheet insulator, said springs having their ends in contact with the walls of the tubular portion of said envelope to resiliently steady said mount from the walls of the tubular portion of said envelope.

5 3. An electron discharge device comprising an envelope having a tubular portion, a mount enclosed by said envelope and comprising an electrode assembly positioned to extend into said tubular portion, a mica plate secured to the end of the mount to extend transversely of the tubular portion of the envelope, and metallic spring spacers provided intermediate their ends with a pair of closely wound coils providing spring clips for engaging the edge of said mica plate with their free ends in contact with the walls of the tubular portion of the envelope to resiliently steady the mount from the walls of the tubular portion of said envelope.

10 4. An electron discharge device comprising an envelope having a tubular portion, a mount enclosed by said envelope and comprising an electrode assembly positioned to be at least partially within said tubular portion, a mica plate secured to the mount to extend transversely of the tubu-

lar portion of the envelope, slots in the edges of said mica plate and metallic spring spacers extended into said slots and having a pair of spring clips for engaging the edge of the mica plate adjacent the slots and having its ends extending beyond the edges of said mica plate to contact the walls of the tubular portion of the envelope to resiliently steady the mount within the tubular portion of the envelope.

15 5. An electron discharge device including an envelope having a tubular portion, a mount enclosed by said envelope and comprising an electrode assembly positioned to extend into the tubular portion, a mica plate secured to the mount to extend transversely of the tubular portion of the envelope, slots in the edges of said mica plate, metallic spring elements positioned within said slots and having two pairs of reversely bent portions disposed on opposite sides of said plate for engaging said mica plate between said reversely bent portions to secure said metallic spring elements to said mica plate with the ends of said spring elements extending beyond the edges of said mica plate to contact the walls of the tubular portion of the envelope to resiliently steady the mount within the tubular portion of the envelope.

20 JULIUS HIRMANN.
